HAMMERING DEVICE

William C. Wymer, United States Navy,
Oregon City, Oreg.

Application December 10, 1945, Serial No. 634,132

2 Claims. (Cl. 1—50)

(Granted under the act of March 3, 1883, as
amended April 30, 1928; 370 O. G. 757)

1

This invention relates to hammering devices and more particularly to telescoping hammering devices.

An object of the invention is to provide an improved hammering device which is of such construction as to facilitate the hammering of articles at elevated heights.

Other objects of the invention are to provide an improved hammering device having means for supporting a fastening element preparatory to and during hammering of the same; to provide an improved hammering device having a telescoping handle so as to permit the hammering of fastening elements at various elevations; to provide an improved hammering device having a pivoted hammer together with remote control means for causing striking movement of the hammer whereby fastening elements may be installed at elevated heights from the ground; and to provide improved elements and arrangements thereof in a hammering device of the character described and for the purposes set forth.

In accomplishing these and other objects of the present invention, I have provided improved details of structure, the preferred form of which is illustrated in the accompanying drawing, wherein:

Fig. 1 is a side elevational view of the upper portion of a hammering device embodying the features of the present invention.

Fig. 2 is a side elevational view, taken at a right angle to Fig. 1.

Fig. 3 is a side elevational view of the lower portion of the device.

Referring more in detail to the drawing:

In Fig. 1, the numeral 1 designates a hammering device having an elongated telescoping handle 2 which preferably consists of a pair of tubular members or sleeves 3 and 4. The lower sleeve 3 is of greater diameter than the upper sleeve 4, whereby the latter telescopes internally of the former. A thumb screw 5 is provided adjacent the upper end of the sleeve 3 for engaging and maintaining the sleeve 4 in adjusted positions relative to said sleeve 3 (Fig. 3).

A pair of parallel, flat bars or legs 6 are fastened to the upper or outer end of the sleeve 4 by spaced pairs of diametric bolts 7 and nuts 8 (Fig. 2). The upper portions of the legs 6 are offset laterally relative to the longitudinal axis of the handle 2 by bending the inner portions of said legs rearwardly, or to the left, and their outer portions forwardly, or to the right (Fig. 1). In this manner, the outer and inner leg portions are parallel to the longitudinal axis of the handle, with

said upper portions being disposed rearwardly or to the left of said handle axis, while the intermediate portions of said legs are inclined at an acute angle thereto.

5 The legs provide a fork or yoke 9 for pivotally supporting a hammer 10 which preferably includes a cylindrical handle or lever 11, of wood or other suitable material, and an enlarged, metallic head 12 mounted transversely upon one end 10 of the lever. A transverse pivot pin or bolt 13 extends through the intermediate inclined portion of the yoke 9 and the lever 11 is provided with a suitable opening 14, as shown in dotted lines in Fig. 2, intermediate its ends for receiving the pin so as to rotatably support said lever between the yoke legs. It is preferable that the opening 14 be formed adjacent the end of the lever opposite the head 12, whereby the weight of said head causes pivoting of said lever in a clockwise direction (Fig. 1). Suitable spacers 15 are confined upon the bolt 13 between the lever and the yoke, while said bolt is fastened in position by a suitable nut 16.

25 For pivoting or swinging the hammer 10, a flexible line or rope 17 is fastened by a screw eye 18 to the end of the lever opposite the head and passes over a sheave 19 which is rotatably supported between the inner portions of the yoke legs by a bolt 20, spacers 21 and a nut 22 (Figs. 1 and 2). Suitable eyes 23 are carried by the sleeves 3 and 4 for receiving the rope 17 and directing the same longitudinally of the handle. An annular weight member or ring 24 is slidably mounted on the sleeve 3 and is fastened to the lower or free end of the rope, whereby reciprocation of the weight relative to said sleeve causes swinging or striking movement of the hammer.

35 If desired, the outer or upper extremities of the yoke legs may be slotted transversely as shown by the numeral 25 for supporting a fastening element 26 in position for hammering (Fig. 1). A transverse plate 27 is disposed beneath or inwardly of the slots 25 for connecting the leg extremities (Fig. 2). The fastening element 26 is of the staple type and preferably carries a body 28, of suitable insulating material, having a wire conductor 29 extending therethrough. As illustrated in Fig. 1, the wire conductor 29 engages within the slots 25 with the insulating body 28 resting upon the plate 27 so as to support the fastening element in position for striking by the hammer; however, the insulating body could be eliminated with the element being supported by resting upon the plate.

Operation

The operation of a hammering device constructed as described herein is as follows:

A fastening element 26, with a wire conductor 29 extending through its insulating body 28, is supported at the upper extremity of the yoke legs 6 by engaging the conductor in the slots 25 whereby the body rests upon the plate 27. The hammering device 1 is then elevated so as to raise the fastening element and conductor to the desired height and such height is controlled by the adjustment of the inner sleeve 4 relative to the outer sleeve 3 of the handle 2.

Due to the pivotal mounting of the lever 11 of the hammer 10, the weight of its head 12 maintains said lever in its retracted or clockwise position. Since the rope 17 connects the weight member 24 to one end of the lever, reciprocation of said weight member downwardly or outwardly of the outer sleeve 3 swings the hammer 10 in a counter-clockwise direction so as to cause its head to strike the fastening element. Release or inward reciprocation of the weight member results in reverse or clockwise pivoting of the hammer to again permit striking movement of said hammer. Upon installation of the fastening element, the hammering device may be readily disengaged therefrom and lowered for the installation of additional fastening elements.

While I have shown but one embodiment of my invention, it is susceptible to modification without departing from the spirit of the invention. I do not wish, therefore, to be limited by the disclosures set forth, but only by the scope of the appended claims.

The invention described herein may be manufactured and used by or for the Government of the United States of America for governmental purposes without the payment of any royalties thereon or therefor.

I claim:

1. A hammering device including, an elongated handle, the handle comprising a pair of telescoping members, means for fastening the members in adjusted telescoped relations, a pair of parallel legs secured to one end of said handle and having

their outer ends offset relative to the handle, the outer ends of the legs having means for supporting a fastening element, a lever pivotally supported between the intermediate portions of said legs, an enlarged head mounted on the outer end of the lever and adapted to strike the fastening element upon swinging of said lever relative to the legs, a rope secured to the inner end of the lever and extending to the far end portion of said handle, a ring slidably mounted on the handle and having connection with the rope for swinging said lever, and a sheave rotatably supported between the inner portions of said legs for receiving said rope.

2. A hammering device including, an elongated telescoping handle, a pair of parallel legs secured to one end of the handle and bent upon themselves so as to provide offset outer end portions, the latter having means for supporting a fastening element, a lever pivotally supported between the intermediate portions of the legs, an enlarged head mounted on the outer end of the lever for striking the fastening element upon swinging of said lever relative to said legs, a weight member slidably mounted upon said handle, and flexible means fastened to and extending from the inner end of the lever to the weight member for swinging said lever upon sliding movement of said weight member.
